United States Patent Office

Des. 206,031
Patented Oct. 18, 1966

206,031

BAG CLOSURE

James B. Swett, Barrington, R.I., assignor to Rexall Drug and Chemical Company, Los Angeles, Calif., a corporation of Delaware

Filed Oct. 6, 1965, Ser. No. 87,339

Term of patent 14 years

(Cl. D58—26)

FIG. 1

FIG. 2

FIG. 3

FIG. 4

FIG. 1 is a perspective view of a bag closure showing my new design, with a bag being shown fragmentarily in broken lines for illustrative purposes only;

FIG. 2 is an enlarged scale side elevational view;

FIG. 3 is a rear elevational view; and

FIG. 4 is a top plan view.

I claim:

The ornamental design for a bag closure, substantially as shown and described.
